UNITED STATES PATENT OFFICE.

JOHN J. RUDDICK, OF NEWTON, MASSACHUSETTS, ASSIGNOR TO THE GAME-WELL FIRE-ALARM TELEGRAPH COMPANY, OF NEW YORK, N. Y.

MESSAGE-RECORDING INSTRUMENT.

SPECIFICATION forming part of Letters Patent No. 662,808, dated November 20, 1900.

Application filed August 7, 1899. Serial No. 726,437. (No model.)

To all whom it may concern:

Be it known that I, JOHN J. RUDDICK, of Newton, county of Middlesex, and State of Massachusetts, have invented an Improvement in Message-Recording Instruments, of which the following description, in connection with the accompanying drawings, is a specification, like letters on the drawings representing like parts.

10. This invention has for its object to improve the construction of message-recording instruments especially adapted for recording fire-alarm and other signals, and many of the novel features are particularly applicable to 15 multiple recording instruments—that is to say, those adapted to be connected with a number of signaling-circuits.

The invention consists in a separate frame or support for each marking-roll, which is 20 pivoted to an independently-detachable arm and elastically connected to the armature of an electromagnet; also, in an ink-conveying roll which at all times bears upon the marking-roll and is supported by and removable 25 with said frame or support; also, in means for moving said frame independent of and in opposition to said electromagnet, so as to draw the marking-roll away from the paper after a predetermined interval of time to 30 thereby limit the length of marks which the marking-roll shall make upon the paper; also, in supporting upon the frame or support the essential coöperating parts of the means employed for independently moving the 35 frame or support after a predetermined interval of time in opposition to the electromagnet in order that said parts may be removed with the marking-roll at any desired time; also, in improved means for starting the recording instrument; also, in improved means 40 for stopping the recording instrument; also, in an improved controlling or governing device for the train, whereby the train will not be retarded at the beginning of its operation—that is to say, when first let off or released—and also in certain details of construction, as will be hereinafter described.

Figure 1 shows in side elevation a message-recording instrument embodying this invention. Fig. 2 is a detail of the paper-moving mechanism. Fig. 3 is a vertical section of the recording instrument taken on the dotted line $\alpha\alpha$, Fig. 4. Fig. 4 is a plan view of

the recording instrument. Fig. 5 is a detail showing one of the marking-rolls and pivoted 55 frame bearing it and the removable or detachable arm to which said frame is pivoted; and also other parts which are supported by said frame. Fig. 6 is a detail of the let-off or tripping lever and means for operating it 60 to stop the train after it has been moved to release the train. Fig. 7 is a detail showing the fan which controls or governs the movement of the train.

The base-plate A has erected upon it two 65 vertical side plates A' A'', which are connected together by a number of cross-bars to constitute a frame which affords bearings and supports for the shafts and operating mechanism.

The main driving-shaft a has fixed to it a sprocket-wheel a' , around which passes a sprocket-chain a^2 , which also passes over a sprocket-wheel a^{30} , secured to a winding-shaft a^{31} , and presents at each side of said shaft a^{31} 70 a loop $a^{32} a^{33}$, and a weight a^{34} , suspended from a roll a^{35} , is supported by the loop a^{32} , and a weight a^{36} , suspended from a roll a^{37} , is supported by the loop a^{33} , and said loop a^{33} passes over and under suitable rolls. The driving 75 gear-wheel a^4 is secured to the shaft a , and it engages a pinion a^5 , secured to a shaft a^6 , and a gear-wheel a^7 is secured to said shaft a^6 , which engages a pinion a^8 , secured to a shaft a^9 , to which is secured the gear-wheel a^{10} , which 80 engages a pinion a^{12} , secured to the escapement-shaft a^{13} , which, as herein shown, carries the fan a^{14} . The train, which is composed 85 of the gearing thus described, is normally held in condition to operate whenever released and 90 is adapted to operate the paper-moving mechanism and other parts of the recording instrument, as will be described.

Ordinarily the fan a^{14} , which controls or governs the speed of the train, is rigidly secured to the shaft bearing it, and as a result the train will start slowly when released, its operation being more or less retarded by overcoming the inertia of the fan, and consequently the speed of the train is varied. Herein I 100 have overcome this difficulty by forming a screw-thread a^{15} on the escapement-shaft a^{13} (see Fig. 7) for a portion of its length, or it may be extended substantially the full length of said shaft, and have provided the fan a^{14} 105 with a nut a^{16} , which is adapted to receive and

turn upon said screw-thread a^{15} , although if the shaft is screw-threaded for its entire length two or more such nuts may be provided on the fan. Whenever the train is released the shaft a^{13} will begin to revolve at its full speed, and, the fan a^{14} being at rest, said shaft will turn within the nut a^{16} ; but there is sufficient friction provided between the screw-thread and nut so that the inertia of the fan is gradually overcome, and it begins to turn slowly at first, but gradually increasing in speed until it revolves at substantially the same speed as the shaft. As the fan is thus revolved it moves along on the shaft a^{13} in one direction—as, for instance, from the full to the dotted line position shown in Fig. 7. Near one end of the shaft a^{13} a disk a^{17} is secured bearing a laterally-projecting stop-pin a^{19} , and when the fan a^{14} has been moved along on the shaft a^{13} until it revolves at a speed substantially equal to the speed of said shaft it will be brought into engagement with said stop-pin a^{19} , and then it becomes as if fixed to the shaft, and is consequently positively revolved by it. Thus it will be seen that whenever the train is started it will immediately begin to operate at full speed. Whenever the train ceases to operate the shaft a^{13} is suddenly arrested; but the fan a^{14} continues to revolve by the momentum imparted to it, and as it thus revolves it moves along on the shaft in the opposite way from the dotted to the full line position shown in Fig. 7, and by reason of the friction provided between the screw-thread and nut its speed is gradually reduced until when it has returned to said full-line position it has almost ceased to revolve. A disk a^{18} is secured to said shaft a^{13} near that end opposite to which the disk a^{17} is secured, which is made substantially like the disk a^{17} and has a stop-pin a^{20} projecting from it, and just as the fan a^{14} ceases to revolve it is brought into engagement with said stop-pin a^{20} . Thus it will be seen that the train may be suddenly stopped without material shock or jar.

To hold the train at rest and to release it whenever desired, a detent b is secured to the outer end of the escapement-shaft a^{13} , (see Figs. 1, 6, and 7,) and a let-off or tripping lever b' is secured at its lower end to a yoke or frame b^2 , which is pivoted at b^3 to one end of a rock-shaft b^4 , having its bearings in the side plates of the machine, said yoke or frame b^2 moving with the shaft b^4 as the latter is rocked and also moving independently thereof on its pivots b^3 at right angles to the movement of said shaft. The upper end of the let-off or tripping lever b' normally engages the detent b and is caused to release said detent b when the shaft b^4 is rocked.

As is usual in instruments of this class, it is designed that whenever the train is released it shall not be again stopped until after a predetermined interval of time succeeding the last impulse—as, for instance, until the rock-shaft b^4 has remained at rest for a predetermined period of time, and to accomplish

this result the let-off or tripping lever b' engages or co-operates with a worm b^5 , which is secured to and projects from one end of a shaft b^6 , and at the inner end of said worm b^5 a deep groove b^7 is formed on the shaft b^6 , which receives said let-off or tripping lever b' when held in position to engage the detent b and arrest the train. This groove b^7 is deeper than the depth of the threads of the worm, so as to insure positively holding the tripping-lever in such position that the rapidly-revolving detent b , when engaging its upper end, will not act to throw said lever out and thereby cause the train to continue to run for an uncertain period of time. The operation of this part of the machine is as follows: Whenever the shaft b^4 is rocked the let-off or tripping lever b' is moved to disengage the 70 detent b , which being secured to the escapement-shaft a^{13} rapidly revolves with said shaft, and as the lever b' is thus moved by the rock-shaft it will be removed from the deep groove b^7 and by means of a spring b^8 attached to it will be moved on its pivots b^3 outwardly against an adjusting-screw b^9 . As soon as the rock-shaft b^4 is restored to its normal position the let-off or tripping lever will be moved into engagement with the worm 80 b^5 , and by said worm will be gradually restored to its normal position, and if said rock-shaft b^4 should remain at rest for a suitable length of time the let-off or tripping lever b' will be moved into engagement with the deep 90 groove b^7 , and when in such position will engage the detent b and arrest the train.

Heretofore releasing devices have been made similar to the releasing device herein shown, yet so far as I am aware the deep annular groove b^7 has never been provided at the end of the worm.

The rock-shaft b^4 extends from side to side of the instrument and has projecting upwardly from it a number of fingers or short arms b^{12} , corresponding to the number of recording or marking devices provided, and each finger b^{12} is so disposed as to be engaged and operated by one of the recording or marking devices, as will be described, so that as 105 any one of said recording or marking devices is operated the shaft b^4 will be rocked to release the train. A spring b^{13} is connected at one end to a hook on the rock-shaft b^4 and at its other end to an adjusting-screw b^{14} , which 110 serves to normally hold the rock-shaft b^4 , with all of its fingers b^{12} , in engagement with said recording or marking devices.

c represents a roll on the shaft a^6 , over which the paper c^{10} travels, and said roll c is provided at each end with a toothed wheel $c' c'$, the teeth of which are made quite sharp and pointed, so as to prick into the paper travelling over it. Just above said toothed wheels $c' c'$ rolls $c^2 c^2$ are supported by brackets, said 125 rolls $c^2 c^2$ revolving freely and bearing upon the paper on the roll c' and holding it permanently in engagement with the toothed wheels $c' c'$. A positively-operating paper-moving

mechanism is thus provided. The roll *c* will be made quite long, so that a wide strip of paper may be employed, which will be sufficient to provide for a number of recording or marking devices.

Several recording or marking devices will be provided, as many as desired; but for the sake of illustration four are herein shown, together with the means for operating them. Referring to Fig. 5, showing one of the recording or marking devices, *d* represents a frame which, as shown, is made as a bell-crank lever, and said frame is pivoted at *d*' to the extremity of an arm *d*², which is detachably secured to a bar *d*³ by means of a screw *d*⁴. The marking-roll *e* is journaled to the upper extremity of one arm of the frame *d* and is adapted to mark upon the moving paper when brought into contact with it. An ink-conveying roll *e*' is journaled to the upper end of an upright spring-supported arm *e*², which bears directly upon said marking-roll *e* at all times, and the said spring-supported arm *e*² is attached to the frame *d* by a screw *e*³ or otherwise. The frame *d* has projecting downwardly from it a short arm or finger *d*⁵, which is made long enough to engage one of the upwardly-projecting arms *b*¹² on the rock-shaft *b*⁴, and as the frame *d* is moved on its pivot the said finger *d*⁵ will in turn move the arm *b*¹², and thereby rock the shaft *b*⁴. A plate *d*⁶, herein shown as made T-shaped, is pivoted at *d*⁷ to the frame *d* at or near the base of the finger *d*⁵, and said plate is slotted at *d*⁸ to receive a pin *d*⁹ on the finger *d*⁵, which limits the movement of said plate *d*⁶ in both directions. A spring *d*¹⁰, which is attached at one end to said pivoted plate *d*⁶ and at the other end to the frame *d*, normally holds said plate *d*⁶ in the position shown in Fig. 5, with the pin *d*⁹ bearing against one end of the slot *d*⁸, and said plate *d*⁶ is moved on its pivot against the tension of said spring *d*¹⁰. A link *d*¹² is loosely and preferably detachably connected at one end to said plate *d*⁶ and at the opposite end to the upper end of the armature-lever *d*¹³ of the electromagnet *d*¹⁴. As herein shown, the armature is normally retracted; but when attracted the link *d*¹² will pull the plate *d*⁶, which will be moved more or less on its pivot as the frame *d* bearing it is moved on its pivot *d*' to move the marking-roll *e* into engagement with the moving paper. Thus it will be seen that the frame *d* is elastically connected with the armature-lever of the electromagnet and is moved or operated by said lever to cause the marking-roll borne by it to engage the moving paper. A spring *d*¹⁵ is attached at one end to a projection *d*¹⁶ on the frame *d* and at the other end to an adjusting-screw *d*¹⁷, supported by the detachable arm *d*², and said spring operates to normally hold the frame *d*, with its marking-roll, removed from the moving paper, and it also serves as the retractile spring for the armature-lever. It will therefore be seen that as the armature-lever vibrates in responding to the operations

of the circuit of the electromagnet the marking-roll *e* will be correspondingly moved into engagement with the moving paper to record the vibrations of said armature-lever.

In many instances the vibrations of the armature-lever vary to correspond to changes of different duration in the circuit of the electromagnet, yet it is desirable that the records made by the marking-roll shall all be substantially alike—that is to say, all substantially of the same length—and to accomplish this result the marking-roll *e* is caused to recede from the paper after it has remained in engagement with it for a certain length of time, and such movement of the said marking-roll is independent of the armature-lever. In carrying out this feature of my invention a curved finger *f* is pivoted at *f*' to a plate *f*², which is in turn pivoted at *f*³ to a projection *d*¹⁶ on the frame *d*, and said curved finger *f* is normally held depressed by means of a flat spring *f*⁴, bearing upon it. The plate *f*², bearing said pivoted finger *f*, has a slot *f*⁵, which receives a pin *f*⁶ on the projection *d*¹⁶, and by means of said pin the movement of the pivoted plate *f*² is limited in both directions. One end of a spring *f*⁷ is attached to the heel end of the finger *f*, and the opposite end of said spring is attached to an upright arm *f*⁸, which is herein shown as made more or less spring-acting, and the tendency of said spring *f*⁷ is to draw the finger and plate bearing it in a direction toward the left until limited by the pin *f*⁶.

i represents a roll formed or provided with a milled or roughened surface and having its bearings in the side plates of the machine, and said roll is positively rotated whenever the machine is in operation, and said roll is located close to and within the curvature of the finger *f*, so that whenever the machine is in operation and the marking-roll *e* moved into engagement with the moving paper the curved finger *f*, borne by the frame *d*, will be brought into engagement with said roll. The finger *f* will be held in engagement with said roll *f* in a yielding manner by reason of the elastic connection of said finger with the frame *d*, and by reason of the milled or roughened surface of said roll the finger *f* will as soon as brought into engagement with it begin to travel upward and forward, and such movement is sufficient to positively move the frame *d* a short distance in opposition to the action of the armature-lever, so as to remove the marking-roll *e* from the moving paper. It will be understood that a certain period of time is required for the curved finger *f* to be thus moved sufficient to in turn move the marking-roll *e* away from the paper, and as a result the marks or records made by the marking-roll will all be of substantially the same length.

As a means of revolving the milled roll *i* a toothed gear *n* is secured to one end of the shaft *a*⁶, which engages a pinion *m*' on the shaft *m*², and said pinion *m*' engages a pinion

m^3 , secured to said milled roll i . It will be seen that as the marking-roll e and frame d bearing it and the other coöperating parts of the marking or recording devices are all secured to an independently-detachable arm d^2 the said marking or recording device may be removed at will, and, as before stated, a number of like marking or recording devices are provided. Any one of them may be removed without disturbing the remaining marking or recording devices, and such feature is of importance in case any repairs are necessary. A toothed wheel m^4 is also secured to said shaft m^2 , which engages a pinion m^5 on the shaft b^7 , to thereby positively rotate said shaft and worm carried by it. The shaft m^2 bears an ink-conveying roll m^8 , and when the frame d is in its normal position, with its marking-roll removed from the moving paper, the ink-conveying roll e' , borne by said frame d , will bear upon said ink-conveying roll m^8 to receive therefrom a supply of ink to be delivered to the marking-roll e . Ink is supplied to said ink-conveying roll m^8 by means of an ink-supply roll m^{10} , which has its bearings in the side plates of the machine, and said ink-supply roll m^{10} is freely revolvable, and its felt or other suitable covering adapts it to receive a large supply of ink, which may be poured thereon as required.

Beneath the ink-conveying roll m^8 a pan n is secured, which receives and directs any drippings of ink down into a suitable reservoir or receptacle n' , adapted to receive them. The reservoir or receptacle n' consists, essentially, of a hopper-like top portion having suitable side walls and formed with an open bottom which communicates with a semicylindrical trough n^2 open at the top and held in a correspondingly-shaped receiver n^3 , and said trough n^2 is adapted to be withdrawn endwise from said receiver n^3 through an opening in one of the side plates, and said trough has secured to it at one end a knob n^5 , by means of which it may be withdrawn at will.

The recording instrument is herein also designed to cause an incandescent electric lamp to glow during the time that it is operating, and to accomplish this result a circuit-operating device for the circuit 20 of an incandescent electric lamp 21 is secured to one of the side plates, as A^3 , and said circuit-operating device consists of a pair of spring-acting contact-pens 22 23, secured to an insulating-block 24, the normal tendency of said spring-acting contact-pens being to close together, and thereby close the circuit 20 when permitted so to do. A lever 25 is pivoted at 26 to the contact-pen 22, and said lever projects beyond the extremity of the pen 22 into the path of movement of the let-off or tripping lever b' , so as to be turned on its pivot by said lever into the path of movement of a pin 27, projecting from the toothed wheel m^5 . A spring 28 (see Fig. 4) is attached to said lever 25, which acts to move said lever on its pivot 26 to throw it out of the path of move-

ment of said pin 27 when the let-off or tripping lever is operated to release the train. As represented in Fig. 1, the let-off or tripping lever b' is in engagement with its detent, thereby arresting the train, and consequently has moved the lever 25 on its pivot into the path of movement of the pin 27, and said pin 27 has raised said lever 25 and spring-acting contact-pen 22 sufficiently to open the circuit-operating device of the circuit 20; but when the said let-off or tripping lever is operated to release the train the lever 25 is moved on its pivot 26 by the spring 28, and is thereby removed from the path of movement of the pin 27, and the spring-acting contact-pen 22 at once engages the contact-pen 23 and closes the lamp-circuit 20. The contact-pens 22 23 will remain closed until such time as the let-off or tripping lever again moves the lever 25 into the path of movement of the pin 27 and said pin has lifted the contact-pen 22 free from the contact-pen 23. A toothed wheel m^5 , bearing the pin 27, is positively driven, as heretofore described, during the entire operation of the machine; but the let-off or tripping lever b' is not returned to its normal position, so as to act to stop the train until a predetermined period of time after the last impulse, and consequently the lamp-circuit 20 will remain closed from the time the machine is started until the machine ceases to operate.

It is obvious that many of the features herein described may be constructed in different ways without departing from this invention and also that some of them may be omitted, if desired.

I claim—

1. In a message-recording instrument, an electromagnet, its armature, a marking-roll, a pivoted frame bearing it elastically connected with and operated by said armature to engage a moving strip of paper, and independent means for moving said frame to move the marking-roll from the paper after a predetermined interval of time, substantially as described.

2. In a message-recording instrument, an electromagnet, its armature, a marking-roll, a pivoted frame bearing it elastically connected with and operated by said armature to engage a moving strip of paper, and independent means for moving said frame to move the marking-roll from the paper after a predetermined interval of time consisting of a finger connected with said frame and a rotating roll having a milled or roughened surface into engagement with which said finger is moved when the marking-roll is moved into engagement with the paper, substantially as described.

3. In a message-recording instrument, an electromagnet, its armature, a marking-roll, a pivoted frame bearing it elastically connected with and operated by said armature to engage a moving strip of paper, and independent means for moving said frame to move

the marking-roll from the paper after a predetermined interval of time consisting of a finger elastically connected with the pivoted frame and a rotating roll having a milled or roughened surface into engagement with which said finger is moved when the marking-roll is moved into engagement with the paper, substantially as described.

4. In a message-recording instrument, an electromagnet, its armature, a marking-roll, a pivoted frame bearing it elastically connected with and operated by said armature to engage a moving strip of paper, and independent means for moving said frame to move the marking-roll from the paper after a predetermined interval of time consisting of a curved finger elastically connected with the pivoted frame and a roll driven by the motor mechanism of the recording instrument having a milled or roughened surface into engagement with which said finger is moved when the marking-roll is moved into engagement with the paper, substantially as described.

25 5. In a message-recording instrument, a marking-roll and an ink-conveying roll, a pivoted frame bearing them, an electromagnet having its armature connected with said pivoted frame, and a positively-driven inking-roll in engagement with which said ink-conveying roll is held when said armature is in its normal position, substantially as described.

35 6. In a message-recording instrument, a marking-roll and an ink-conveying roll, a pivoted frame bearing them, an arm bearing said pivoted frame detachably secured to the frame of the machine, and an electromagnet having its armature detachably connected with said pivoted frame for operating it, substantially as described.

45 7. In a message-recording instrument, a marking-roll, a frame bearing it, an arm detachably secured to the frame of the machine to which said marking-roll frame is pivoted, an electromagnet having its armature connected with said pivoted frame, and a spring attached to one end to said pivoted frame and at the other end to an adjusting-screw supported by said detachable arm, substantially as described.

50 8. In a message-recording instrument, a marking-roll, a frame bearing it, an arm detachably secured to the frame of the machine to which said marking-roll frame is pivoted, an electromagnet, its armature, and a detachable link connecting said armature with said pivoted frame, substantially as described.

60 9. In a message-recording instrument, a marking-roll, a frame bearing it, an arm detachably secured to the frame of the machine to which said marking-roll frame is pivoted, an electromagnet having its armature connected with said pivoted frame, and independent means for moving said pivoted frame to remove the marking-roll from the paper after a predetermined interval of time, a cooperator-

ing part of which is borne by said pivoted frame, substantially as described.

10. In a message-recording instrument, a number of marking-rolls, a corresponding 70 number of independent frames bearing them, independently-detachable arms secured to the frame of the machine to which said marking-roll frames are pivoted, electromagnets with the armatures of which said pivoted frames 75 are connected, and means for conveying a wide strip of paper along near said marking-roll to be engaged by any one of them, substantially as described.

11. In a message-recording instrument, a 80 number of marking-rolls, a corresponding number of independent frames bearing them, independently-detachable arms secured to the frame of the machine to which said marking-roll frames are pivoted, ink-conveying rolls 85 also borne by said pivoted frames which at all times bear upon said marking-rolls, a positively-driven inking-roll which said ink-conveying rolls are adapted to engage, and electromagnets with the armatures of which said 90 pivoted frames are connected, substantially as described.

12. In a message-recording instrument, a paper-moving train, a number of recording or marking devices each having a projection d^5 , 95 a rock-shaft, a number of fingers b^{12} corresponding to the number of recording or marking devices borne by said rock-shaft and adapted to be engaged by said projection d^5 , a let-off or tripping lever for said paper-moving train secured to said rock-shaft and a number of electromagnets corresponding to the number of recording or marking devices, the armatures of which are connected with and adapted to operate said recording or 105 marking devices to thereby operate said let-off or tripping lever and release said paper-moving train, substantially as described.

13. In a message-recording instrument, a train, a let-off or tripping lever therefor, an 110 electromagnet for operating said lever to release the train, a spring for moving said lever out of position to engage and stop the train, and a worm for returning it into position to stop the train having at one end a groove 115 deeper than the threads of the worm which receives said lever when in position to stop the train, substantially as described.

14. A train, a fan governing the operation of said train, a screw-rod connected with and operated by said train upon which said fan is mounted and along which it is movable in both directions and a stop for the fan at each end of said screw-rod, substantially as described.

125 In testimony whereof I have signed my name to this specification in the presence of two subscribing witnesses.
